UNITED STATES PATENT OFFICE.

HARRY A. FOOTHORAP, OF HARRISBURG, PENNSYLVANIA, ASSIGNOR TO ELLIOTT-FISHER COMPANY, A CORPORATION OF DELAWARE.

CROSS-FOOTING REGISTER.

Application filed May 3, 1924. Serial No. 710,803.

REISSUED

To all whom it may concern:

Be it known that HARRY A. FOOTHORAP, a citizen of the United States, residing at Harrisburg, in the county of Dauphin and State of Pennsylvania, has invented certain new and useful Improvements in Cross-Footing Registers, of which the following is a specification, reference being had therein to the accompanying drawing.

This invention relates to computing mechanisms, particularly of the type known as cross footing registers for writing adding machines.

The object of the invention is to provide a cross footing register with a toggle locking, two way carrying or transfer mechanism of the general character described in my co-pending application No. 710,802, and to associate therewith a resetting mechanism similar in principle to the resetting mechanism of said application, but varied to conform to the requirements of a cross footing register of the type disclosed in my Patent No. 1,455,196.

To the accomplishment of this general object and others subordinate thereto, one embodiment of the invention resides in the construction and arrangement of parts herein-after fully described and illustrated in the accompanying drawings.

In said drawings:

Fig. 1 is a vertical section through a cross footing register constructed in accordance with my invention.

Fig. 2 is a side elevation of the register showing elements of the resetting mechanism mounted on the exterior thereof.

Fig. 3 is a detail section of the structure shown in Fig. 2.

Fig. 4 is a rear view of the register with the casing in section.

Fig. 5 is a vertical section through the register.

Fig. 6 is a side elevation of one of the carrying devices and immediately associated parts.

Fig. 7 is a sectional elevation of the subject matter of Fig. 6.

Fig. 8 is a detail perspective view of the two bearing blocks.

Figs. 9 and 10 are detail sectional views showing the carrying mechanism at different stages of the carrying operation, the normal positions of certain parts of the resetting mechanism being indicated in dotted lines.

Figs. 11 and 12 are similar views of the carrying mechanism during and after resetting, with the elements of the carrying mechanism in different positions assumed by them when operated to reset the carrying mechanism.

The particular machine, an embodiment of which is under consideration, is the Elliott-Fisher bookkeeping machine of commerce. This machine is of the class known as flat platen typewriters equipped with adding mechanism consisting of column registers and a cross footing register. The column registers are associated with different columns of the work sheet and the cross footing register is common to any or all of the columns, provision being made for its operation, for either addition or subtraction, simultaneous with the operation of different column registers.

The general assemblage is shown in Fig. 1 wherein 1 indicates the traveling carriage on which the keys and printing mechanism are mounted, 2, the cross footing register mounted on and movable with the carriage, and 3, one of the column registers mounted on a relatively fixed register bar in rear of the carriage.

The cross footer register and the column register are operated simultaneously from keys (not shown) which, through intermediate mechanism, operates a master wheel shaft 4 on which is mounted a master wheel 5 presented to successive number wheels of the column register as the carriage moves from one denomination to another and rotated different distances by the keys according to their numerical value. Thus as digits are printed in a column the corresponding number wheels of the column register are operated to an extent determined by the value of the printed digits.

Mounted in the casing of the cross footer 2 are a series of number wheels 6 occupying different denominational positions and operated by a master wheel 7 movable longitudinally of a squared shaft 8 geared to the shaft 4 by variable gearing 9. This gearing 9 serves to transmit motion from the shaft 4 to the master wheel shaft 8 of the cross footer in either of two directions for the purpose of operating the number wheels 6 for addition or subtraction through the master wheel 7.

Geared to the denominational members or

number wheels 6 are a series of indicating wheels 10, the digits on the peripheries of which are exhibited at a sight opening 11 in the cross footer casing.

- 5 Directly below the number wheels 6 are mounted a series of carrying or transfer devices, each of which includes a carrying head 12 having a fixed axis on a shaft 13, and a link 14 pivoted to the lower end of
 10 the head and to an operating lever 15 urged in one direction by a suitable motor, as for instance, a spring 16. The relation of the parts is such that normally the pivotally connected members 12 and 14 of each carrying device are disposed in alignment with the axis 13 which acts as a dead center opposing the power exerted by the spring 16. In this normal relation of the parts the carrying devices constitute toggle locks
 15 20 which nullify the motor springs 16 so that each carrying device normally occupies a central position. As soon, however, as a carrying device is broken or flexed in either direction from this central position, the dead center relation of the parts is destroyed and the motor spring becomes effective to swing the head 12 and thereby effect the carrying operation.

25 This initial flexing of the carrying device 30 is accomplished by the adjacent number wheel 6, one tooth of which is widened to form a carrying lug 17 which engages a trip 18 extended upwardly from the head 12. On the head, and mounted at opposite sides 35 of the axis thereof, are a pair of carrying fingers 19 pivoted at 20 and having associated therewith, locking dogs 21. Each combined finger and locking dog yields in one direction against the resistance of a spring 22, but by reason of engagement with the side of the head 12 is unyielding relative to the head in the opposite direction.

40 As described in my application aforesaid, this construction and arrangement of the carrying devices results, when the number wheel moves from "0" to "9" in addition or from "9" to "0" in subtraction, in the engagement of the lug 17 with the trip 18 and in the flexing or breaking or tripping of the carrying device in one direction or the other. The motor spring 16 becomes effective to complete the carrying operation through the engagement of one of the dogs 19 with the next higher number wheel as soon as the 45 alignment of the elements 12 and 14 is disturbed. The members 14 are extended below the operating levers 15 and are provided at their lower ends with rollers 23 which engage arcuate depressions 24 in detent levers 50 55 60 65 25 urged in the holding direction by springs 26 attached to a hook bar 27 and at their lower ends to the extremities of the detents 25 which are fulcrumed in a bearing block 28 and are guided both by said block and a second bearing block 29.

The described mechanism is substantially that of my application hereinbefore referred to, except for certain variations which adapt the mechanism for use in this particular type of register, the levers 15, for instance, being of different form and mounting, the arrangement of the motor springs being different and the construction and arrangement of the detents 25 and the mounting of their springs 26 being likewise varied in matters of detail. The principal variation occurs in the resetting mechanism for the carrying devices. The resetting of the carrying devices and the restoration of the motor springs to normal tension is accomplished by resetting mechanism which includes two resetting yokes 30, the transverse resetting bars 31 of which extend across the entire series of carrying devices at opposite sides thereof.

70 The yokes 30 are swung from the shaft 13 and the walls of the casing are formed with arcuate slots 32 accomodating the movement of the bars 31, and through which said bars extend to the exterior of the casing (see Fig. 2). Fulcrumed on the exterior of the cross footer casing are two oppositely disposed bell cranks 33 and 34 having bifurcated ends 35 engaging the ends of the resetting bars 31. The opposite ends of the bell cranks overlap, as shown in Fig. 2, one being bifurcated or slotted, as indicated at 36, to engage a pin 37 on the other. This slot and pin connection compels the bell cranks to move in unison, but in opposite directions. Also fulcrumed upon the exterior of the cross footer at 38 is a resetting lever 39 terminating at one end in a resetting key 40, and at its opposite end in a hook 41 for the attachment of a spring 42 secured at its opposite end to the casing, as shown at 43. A link 44 is dropped down from the lever 39 and is connected to the bell crank 34 as shown. 45 50 55 60 65 70 75 80 85 90 95 100 105 110 115 120 125 130

It will now be seen that when the carrying mechanism has been operated and occupies the position shown in Fig. 10 or a similar position at the other side of the center, it will be retracted to its normal central position by the simultaneous swinging of the resetting yokes 30, the setting bars of which move toward the center line of the carrying devices and thus restore them to dead center relation, regardless of which way they have been flexed or operated. This swinging movement of the resetting yokes is effected by the depression of the key 40, which, through the intermediate link 44, will cause the two connected bell cranks 33 and 34 to swing toward each other and thus swing the yokes to which they are connected.

When the carrying devices have been reset, the release of the key 40 will retract the resetting mechanism and as the motor springs 16 have been restored to normal ten-

sion and the members 14 again engage with the detents 25, the mechanism will be in condition for a reoperation.

From the foregoing, the construction and 5 operation of the illustrated embodiment of the invention will be clearly understood, but I reserve the right to effect such modifications thereof as may fall within the scope of the claims.

10 What I claim is:

1. In a mechanism of the character described, the combination with carrying devices, of bearing blocks located at opposite sides thereof, operating levers and detents 15 fulcrumed in their respective bearing blocks and each guided by both blocks, and springs connected to said levers and detents.

2. In a mechanism of the character described, the combination with a carrying 20 mechanism and bearing blocks located at opposite sides thereof, of operating levers fulcrumed in one of the bearing blocks and guided by the other, detent levers fulcrumed in the last named block and guided by the 25 block first named, and springs connected to the free ends of the levers and detents and located outside of the bearing blocks.

3. In a mechanism of the character described, the combination with carrying 30 mechanism movable in either of two directions from a central position, resetting yokes for said carrying mechanism, bell cranks directly connected to each other and to the yokes, and a resetting lever for operating the bell cranks.

4. In a mechanism of the character described, the combination with carrying devices and resetting yokes therefor, of connected bell cranks for operating the yokes, 40 a key connected to the bell cranks to operate the same, and means for retracting the key.

5. In a mechanism of the character described, the combination with carrying mechanism and a pair of resetting yokes 45 therefor, of oppositely disposed bell cranks directly connected to each other and to the yokes, a resetting lever, a link connecting the resetting lever to one of the bell cranks, and means for retracting the resetting lever.

6. In a mechanism of the character described, the combination with a casing, of carrying mechanism within the casing, a pair of resetting yokes also within the casing but extended outside thereof, a pair of 55 bell cranks mounted outside of the casing and engaging the yokes, means connecting the bell cranks to compel their movement in unison but in opposite directions, and a resetting key for operating the bell cranks.

7. In a mechanism of the character de-

scribed; the combination with a casing having arcuate slots in a wall thereof, of carrying mechanism within the casing, resetting yokes cooperating with the carrying mechanism and including resetting bars extended 65 through the slots in the casing, connected levers mounted on the exterior of the casing and engaging the resetting bars, and a resetting key for operating said levers.

8. In a mechanism of the character described, the combination with a casing having arcuate slots in one wall thereof, a carrying mechanism within the casing, resetting yokes cooperating with the carrying mechanism and including resetting bars extended 70 through the arcuate slots, bell cranks fulcrumed on the outside of the casing and connected to each other and to the resetting bars, a resetting lever mounted on the casing and connected to one of the bell cranks, and means for retracting the lever.

9. In a mechanism of the character described, the combination with a casing having arcuate slots in one wall thereof, a carrying mechanism within the casing, resetting yokes cooperating with the carrying mechanism and including resetting bars extended 75 through the arcuate slots, bell cranks fulcrumed on the outside of the casing and connected to each other and to the resetting bars, a resetting lever mounted on the casing, a link connecting the resetting lever with one of the bell cranks, and a retracting spring for the resetting lever.

10. In a mechanism of the character described, the combination with a casing having arcuate slots in one wall thereof, a carrying mechanism within the casing, resetting yokes cooperating with the carrying mechanism and including resetting bars extended 80 through the arcuate slots, bell cranks fulcrumed on the outside of the casing and connected to each other and to the resetting bars, a resetting lever mounted on the casing, a link connecting the resetting lever with one of the bell cranks, and a retracting spring for the resetting lever.

11. The combination with spaced bearing and guide blocks of a set of operating levers and a set of detent levers, each set of levers being mounted in one block and guided by the other block, denominational members, and carrying mechanism therefor cooperating intermediate of the block with both sets 85 of levers.

In testimony whereof I hereunto affix my signature.

HARRY A. FOOTHORAP.
